MACHINE FOR SEAMING LIDS ON CANS

Frank Oscar Levi Chorlton, Bury, England

Application December 5, 1934, Serial No. 756,165
In Great Britain December 14, 1933

9 Claims. (Cl. 113—24)

This invention relates to machines for seaming on the lids of cans, and more particularly when the process of seaming has to be carried on in a chamber which in some cases may be subjected to a vacuum, and in other cases may be charged with an inert gas so that the can during the process of seaming is either subjected to vacuum or charged with an inert gas, as the case may be.

In the drawings:—

Fig. 1 is a front elevation necessarily drawn, from considerations of space, to a comparatively small scale and shows the general arrangement of the machine.

Fig. 2 is an elevation to a larger scale of the portion of the machine above the line X, X, and

Fig. 3 is an elevation of the portion below the said line.

These two views when placed in line, together constituting a view similar to Fig. 1 but to a larger scale.

Figs. 4, 5 and 5A are side elevations corresponding with Figs. 2 and 3.

Fig. 5A is the portion on the left of the line y, y.

Fig. 5B is a part plan in section on a horizontal plane passing through the axis of the driving shaft.

Figs. 6 to 18 illustrate the construction of the separate mechanisms.

Fig. 6 is a fragmentary elevation showing a portion of Fig. 5 with the table and the auxiliary sealing chamber in medial section; Fig. 7 is a fragmentary side elevation showing the centering means; Fig. 8 is a corresponding plan; Fig. 9 is a detail view of one of the centering sectors; Fig.

10 is a plan view of one of the gripper bars; Fig. 11 is a detail view showing the conveyor free-wheel device, worm wheel and worm; Fig. 12 is a fragmentary elevation in medial section showing the bottom of the main casing and the rotary valve; Fig. 13 is a plan view of the bevel gearing for operating the rotary valve; Fig. 14 is a fragmentary elevation showing the device which renders the clenching mechanism inoperative until the can is in position to be clenched; Fig. 15 is a fragmentary plan view showing the mode of actuating the can seaming rollers; Fig. 16 is a detail showing the rack and pinion for actuating the shaft r¹2 of the gripper mechanism; Fig. 17

is a fragmentary portion of Fig. 1 to a larger scale showing the means for operating the gripper bars and the clenching mechanism, and Fig.

18 is a detail view showing how the clenching and lid locating mechanism is operated.

Referring first to Figs. 1 to 6:—A is the main

frame of the machine and it is so arranged as to provide a main vertical member a¹, to one face of which the main mechanisms to be operated are attached, and to the opposite face of which the sleeves which carry the cam-operated sliding members are attached; the top a² of the frame carries a main bracket for the driving shaft and this is so arranged that the vertical cam shaft driven thereby is located in a suitable recess and in convenient relationship to the said sleeves and sliding members. The arrangement permits the location of the mechanisms for actuating the several parts to be disposed in vertical succession with a corresponding arrangement of the cams in vertical succession on the cam shaft. This general arrangement gives a very compact, convenient and accessible design.

The main driving shaft B is situated at the top of the machine and is driven by belt and pulleys b¹ from a motor or line shaft. A pulley b² on the end of this shaft drives the vacuum pump, and the inert gas exhauster when one is fitted.

The shaft B drives the seaming head c through spiral wheels b¹⁰, b¹¹ or other suitable gear and is geared to the vertical cam shaft D through the combined worm d¹⁰ and worm-wheel d¹ and slipping clutch d², d³. On this vertical shaft the cams operating the motions of the machine are situated. By their disposition in this way all the cams can be designed with operating faces on which the cam rollers run parallel to the axis of the shaft, which enables them to be easily constructed, inspected and adjusted.

One of the bearings of the shaft B is carried in the casing E which also encloses the gear wheels by which the shaft is connected with the seaming head c, the latter being enclosed in the casing C, to the upper facing of which the casing E is attached, thus ensuring alignment between the parts connected by the gear wheels. The other end of the shaft B is carried in bearings formed in a casing F which also serves to enclose the bearings of the cam shaft D and the worm wheel d¹ which is concentrically arranged in relation to a slipping clutch d², d³, one element d² of which is keyed to the upper end of the shaft D, and the other element d³ of which is pressed into adjustable frictional contact by the springs d⁴ with an annular flange on the inside of the rim of the worm wheel d¹, said flange being interposed between the two members d² and d³.

This drive forms an exceedingly convenient arrangement for coupling the two shafts B and D which rotate at widely differing speeds, and the interposition of the slipping clutch obviates

50 55

the necessity of providing the usual safety shearing pin or the like safety device, which pin is, in the hurry of re-starting, frequently replaced by one of a material not suitable for the purpose; 5 the slipping clutch enables the maximum torque which it is considered safe to transmit to the mechanism to be adjusted accurately, and should a jam occur it is simply necessary to clear the jam and start up the machine which remains in correct adjustment.

Where the nature of the movement to be imparted to a particular device or devices is such as can be derived from cams, cranks or eccentrics, the latter are mounted on the single cam shaft D.

15 The seaming head c located in a main sealing chamber C is continuously driven and the seaming rollers c5 are moved radially into operative relationship with the can lid through the instrumentality of actuating rollers c6 bearing on a vertically adjustable member c4', which to render the seaming head operative is raised vertically.

The member c4' which is rotated at the same speed as the seaming head is moved vertically upwardly by a cam c1 bearing on a cam roller c2

25 mounted on an adjustable sliding transmission member c3 non-rotationally carried in the sleeve c4; a roller c9 on the opposite end of the sliding transmission member c3 engages the vertical arm of a bellcrank lever c10, the horizontal arm of

30 which has the usual roller and groove connection with the member c4' (see Fig. 15); the horizontal portion of the lever c10 may be bow-shaped so as to embrace the member c4' with pins c20 in opposite arms engaging a groove c21 in c4', or 35 the bellcranks may be duplicated and the roller c9 engage the centre of a connecting part between the levers.

The sealing chamber C in some forms of machines is so arranged that a vacuum may be 40 maintained therein; in other types of machines an atmosphere of inert gas is maintained in the chamber C, which is provided with an inspection window c11 and the usual gauge c12. At the bottom c15 of the chamber C is an opening c13 controlled by a shutter valve H.

In order to ensure the proper release of the cans in succession from the seaming rollers, a vertical movable rod G is mounted so as to be 45 slideable concentrically within the casing E; reciprocating motion is imparted to this rod by

50 means of a cam g1 mounted on the cam shaft D; the cam imparts, through the roller g2, reciprocating movement to the sliding transmission member g3 carrying the roller g2 and non-rotatably mounted in a guide g4; a bellcrank lever g5 is pivotally carried from the guide g4 and one arm of the lever is connected by a link to the sliding member g3; the other arm is connected by the connecting rods g6 to one end of

55 a pair of levers g7 fulcrumed on the link g8 carried from the casing E, the other end of the said levers being pivotally connected to a collar g9 secured to the rod G by lock nuts which permit a vertical adjustment of the rod G relatively to the collar. This collar is so adjusted and the cam g1 is so set that the bottom end of the rod G is, whilst a can is being seamed, almost in contact with the top of the lid thereof, and the shape of the cam is such that the lower end of the rod

60 follows the downward movement of the can when the sealing operation is completed; if therefore a can should jam the rod G effects its release.

70

The bottom c15 of the casing C which, as stated, forms the main sealing chamber is provided with a transverse rectangular groove in

which slides a shutter H, the surfaces being scraped to form a gas-tight fit. Normally this shutter, which constitutes the valve for the opening c13, is closed, but when, preparatorily to a can being introduced into the sealing chamber C and after the opening c13 has been put into fluid-tight connection with the interior of an auxiliary chamber M (hereinafter described), the shutter H is opened to permit the introduction of the can without undue loss of vacuum or gas from the sealing chamber.

The shutter H is operated by the cam h1, the arrangement being as follows:—The cam engages the cam roller h2 mounted on the head h5 of a sliding transmission member h3 non-rotatably mounted in the guide h4. A fixed bracket h7 in which the cam shaft D rotates freely is carried from the main frame by a suitable transverse bar and forms the fulcrum of a lever h8, the upper end of which is connected by a link h9 to the sliding shutter H; the other end or tail h10 of the lever h9 slides in a transverse hole in the pivot pin h11.

The cam h1 is so shaped and timed that it imparts, just before the can is introduced into the sealing chamber C, an opening movement to the valve H and the ratio of the arms of the lever h8, h10 is such that a rapid opening movement is imparted.

K is the main table of the machine and it is 30 adjustably attached to the facing a1 of the main frame so that it can be raised and lowered to suit cans of different vertical dimensions.

M is the auxiliary sealing chamber or cylinder (shown in Fig. 6, and in chain-dotted lines in Fig. 1) mounted on the table K so as to be capable of sliding movement relatively thereto concentrically with the axis of the seaming head.

Whilst the can is being fed so as to come under the seaming head the chamber M occupies its 40 lowest position with its top below the table K; when the can has been concentrically located relatively to the seaming head and is ready to be introduced therein the cylinder M is moved upwardly so that its upper edge makes joint with the gasket jointing ring m10 which is inset in the plate m11 having a central opening coinciding with the opening c13 in the bottom of the sealing casing C.

Vertical movement is imparted to the cylinder M by a cam m1 mounted on the shaft D engaging a roller m2 on the sliding transmission member m3 mounted in the guide m4; the roller m5 on the other end of the transmission member engages with the plane surface of a lever m6 mounted on a shaft m7 eccentrically pivoted in a bracket carried from the table K; levers m8, one at each side of the central axis of the machine, are connected by links m9 to the chamber M, the pins connecting the links passing through slots in the portion K1 of the table K which encircles the chamber M; or as shown in Fig. 6, the pins m13 which connect the links m9 to the said chamber may be wholly enclosed in the thick bottom m14. The levers m8 are fitted with springs m12 which return the chamber M to its lowermost position. m14' is a screw mounted in a bracket attached to the lever m8 and is used to adjust the angle between m8 and m6.

The amount of vertical movement to be imparted to the sealing cylinder will vary in accordance with the vertical position in which the table K is set to accommodate the different heights of cans, and the travel of the sealing cylinder will therefore vary in accordance with the 75

distance at which the table is set below the sealing chamber C, as described in my British Patent No. 381,343 of 1931.

By providing the arm m_6 with a plain surface which engages the roller m_5 and pivoting the arm to the table when the latter is lowered, the distance of the roller m_5 from the pivoting axis of the bellcrank lever will be reduced and the velocity ratio due to the bellcrank lever increased. The adjustment for the movement of the chamber M is therefore automatically obtained by the movement of the table.

The eccentric pivoting of the bellcrank lever enables the upper position of the chamber M to be adjusted so that it exercises the necessary pressure on the gasket ring m_{10} to ensure a gas-tight joint.

P is the movable table on which the can is supported, and by which it is moved into proper relationship with the seaming mechanism; the table has a shank p_{10} concentrically arranged within the boss of the chamber M and movement is imparted to the table by the cam p_1 engaging the roller p_2 on the sliding transmission member p_3 non-rotatably mounted in the guide p_4 . The other end of the member p_3 carries a roller p_5 which engages a lever p_6 mounted on the shaft p_7 .

Mounted on the shaft p_7 is an actuating lever p_8 , the curved end of which engages the adjustable flange p_9 on the lower end of the shank p_{12} which is a continuation of the hollow shank p_{10} of the movable table; the lever p_8 is actuated by the lever p_6 through a lever p_{11} connected to p_6 by a compression spring housed in the spring box p_{21} , and by the adjustable stop p_{22} ; this spring provides the elastic upward pressure on the can as it comes to the beading position. The cam p_1 is so shaped and timed that it imparts vertical movement to the lifting table after the sealing cylinder is in position and the valve or shutter H has been opened, and in its top position the table brings the can lid into operative position under the seaming rollers.

The shank of the moving table is made in two concentric parts p_{10} and p_{12} axially slidably relatively to each other, the two sliding parts being fitted with a clamping bracket p_{13} so that the distance of the flange p_9 from the lifting table may be adjusted to accommodate different lengths of cans; a guide p_{14} being provided to prevent turning.

The lifting table P is provided with a centering device T (see Fig. 6) comprising two centering sectors T which fit in the groove between the two flanges t_5 formed in the rim of the table P. The sectors have pivoted to them the upper ends of two pairs of links t_8 , and the lower ends of the respective pairs of links are pivotally attached to a transverse pivot pin t_1 , passing through a hole in the tension rod t_1 , and through a slotted hole in the table shank p_{10} ; the rod t_1 passes down through the hollow bore of the two part shank p_{10} , p_{12} of the table P passing out of the part p_{12} through the flange p_9 (see Fig. 3); the lower end of the rod t_1 is anchored by two tension springs t_3 (see Fig. 5); the upper ends of the springs are attached to a cross bar t_4 secured in position on the lower part of the rod t_1 by nuts t_{10} ; the lower ends of the springs are fixed to a cross bar t_{11} carried by a slider t_{12} adjustably mounted on a bracket t_{13} ; a stop arm t_2 is also secured to the bracket t_{13} and by contact with the lower nut t_{10} serves adjustably to limit the downward movement of the rod t_1 . It will be

seen from Figs. 3 and 7, that as the table P is raised to lift the can to the seaming rollers, the two springs t_3 by the pull they exert on the rod t_1 through the cross bar t_4 arrest the upward movement of the rod t_1 and pivot pin t_1 , and that this produces relative movement between the pin t_1 and the table P. Movement of the table P and sectors T relatively to the pins t_1 carried by the part t_1 and permitted by the slot in the part p_{10} , draws the upper ends of the links t_8 together and this causes the sectors T to close in and centre the can J and hold it fixed centrally as the table P ascends, the springs t_3 yielding and providing the constant pull on the pivot pin.

It will be seen from Fig. 6 that the table shank p_{10} fits the bore of the bottom m_{14} of the chamber M, and the bore of the shank m_{15} of the latter.

R are the grippers by which the cans are moved along the table into position over the lifting table P; the grippers are given a transverse and longitudinal reciprocating motion, the former to grip the can and the latter to propel it along.

Each gripper R is carried by two horizontal levers r pivoted to the ends of two levers r_6 respectively keyed to two longitudinally traversing bars r_7 ; the four bars r_7 and cross bars r_8 form a frame.

The oppositely disposed pairs of bars r_7 are connected to the machine frame so as to be angularly and longitudinally movable relatively thereto, and at the right hand ends these bars are connected together by a cross bar r_8 in which the bars are rotatable. The cross bar r_8 is connected by links r_{18} to the end of a lever r_{14} (see Figs. 3 and 5) keyed to a shaft r_{17} , said links being pivotally connected at one end by the pin r_{15} to the centre of the cross bar r_8 and being connected by the pin r_{21} to the end of the lever r_{14} . The lever r_{14} is shown in Fig. 5, but is not shown in Fig. 1. The end of the lever r_{16} is operated by the cam r_{10}' (see Fig. 3), the lever having a depending roller which fits a cam groove in the cam r_{10}' . The lever r_{16} is arranged tangentially with reference to the cam groove and is therefore reciprocated as the cam r_{10}' rotates; this reciprocating movement is transmitted through the vertical shaft r_{11} , lever r_{14} and links r_{18} to the transverse bar r_8 ; thus the cam imparts longitudinal motion to the frame comprising the bar r_8 and the four pivoted bars r_7 , and through the latter, the levers r_6 and the lever r to the gripper bars R.

One bar of each pair of bars r_7 has slidably keyed to it a lever r_9 , and the grippers R are reciprocated transversely by a pair of radius rods r_{10} connected at the upper ends to the respective levers r_9 and at the lower ends to the end of a lever r_{11} keyed to a shaft r_{12} . The lever r_{11} is reciprocated by a cam r_1 having a cam groove in its lower face with which engages a pin roller r_2 attached to the head of the sliding transmission member r_3 , non-rotationally guided in the bracket r_4 . The member r_3 carries a toothed rack r_{30} (see Fig. 16) which gears with a pinion r_{31} keyed to the shaft r_{12} . The rack and pinion are housed in a casing r_{32} formed by an extension of the bracket r_4 . The angular movement of the shaft r_{12} is employed as described below to actuate a detent-controlled lever to operate the clenching gear.

The rods r_7 extend for a considerable length over the tables, and there are two pairs of levers r and the levers r_6 on each pair of rods; the respective adjacent ends of the levers r are con-

nected together by respective transverse rails R which (see Figs. 5 and 10) constitute the grippers, the gaps in which as they move inwardly, engage the can. The cans are led to the grippers by projections w1 on the chain conveyor W which is driven by the chain wheels on shafts w2 and w3 (see Fig. 5A). A spur wheel w4 (see Fig. 11) is connected to the shaft w3 by a free-wheel device w5 and engages a rack w6 formed on the end of one of the bars r7. When the bar r7 and the grippers are moved in the direction of the arrow w7 the conveyor chain feeds forwardly and feeds the cans to the gripper R. At the end of this stroke the gripper returns but does not in its return movement drive the conveyor, but grips the foremost can and carries it first under the clenching mechanism, the can having a "dwell" whilst the clenching is effected, after which the can is brought by the next movement of the gripper over the centre of the lifting table where there is another "dwell" whilst the can is centered and sealed; at the next stroke of the gripper the can is removed from the lifting table.

The clenching mechanism S is of the type described in the specification to my Patent No. 1,997,102. The mechanism described in my said prior specification is operated by a lever having a toothed quadrant (shown at 16 and 16a Fig. 1 of my said specification). The clenching mechanism (see Figs. 2, 4 and 18 herein) is as described in my said specification, s30 being the clenching members, s31 an operating member having bevel teeth s32 with which gear corresponding teeth on the lever s5 engage, the rack to hold the nested lids being shown at s14 (Fig. 4).

The clenching mechanism is actuated by the same cam r1 and shaft r12 which operate the grippers; there is loosely mounted on the shaft r12 a lever s1 (see Fig. 17) on which is pivoted a pawl s2 adapted to engage a projection r20 fixed to the shaft r12; when this pawl engages with the said projection the lever s1 is moved upwardly and, through the rod s3, actuates one arm s4 (see Figs. 1, 2 and 18) of a bellcrank lever s4, s5 mounted on a shaft s6; the portion s5 of the bellcrank lever is a portion of a bevel wheel sector which gears with the bevel wheel by which motion is imparted to the clenching apparatus. The detent s2 is, when there is no can under the clenching mechanism, rendered inoperative to be engaged by the projection r20 when the latter commences to make its upward stroke by a lever s7 pivoted at s8 and connected by the rod s9 to a lever s10 (see Fig. 14) fixed to one end of a shaft s11 on which shaft is also keyed a lever s12 the upper end of which is connected to a transversely movable part s13 engaged by the successive cans as they come under the clenching mechanism, the arrangement being such that when there is no can in position to be clenched the lever s12 is not actuated by the part s13 and at the beginning of the upward stroke of the projection r20 the lever s7 holds the detent s2 clear of the projection r20, so that no motion is imparted to the lever s1 to actuate the clenching mechanism.

In those cases in which it is desired to effect the seaming process in a seaming and sealing casing C charged with an atmosphere of an inert gas such as carbon dioxide or nitrogen, it is, of course, necessary to exhaust the air from the chamber M and the can before the shutter H is opened; in such cases a port v1 (see Figs. 12 and 13) is formed in the bottom of the main sealing chamber C,

which port opens into the interior of the chamber M when the latter is in its top position; this port communicates with the port v2 in the casing v3 of the rotary valve V which just prior to the opening of the shutter H, puts the interior of the chamber M and can into communication through a port v4 with an exhausting pump, said valve then closing, whereupon the shutter valve H is opened and the can introduced into the main sealing chamber to be seamed. After the can has been retracted into the chamber M and the valve H closed there will be a charge of the inert gas in the chamber M and where it is desired, for reasons of economy, to save this gas, the said rotary valve connects the said port v1, through the port v5, to a suitable pump which withdraws the said inert gas from the chamber M and returns it to the main sealing chamber C after which the said port v1 is connected by the port v6 to the atmosphere and the chamber M lowered and the can removed.

The valve is operated by connecting it to the cam shaft D by bevel gear v7.

The pump is operated by any suitable driving means connecting it to the driving shaft B, for instance, to the pulley b2.

k2 is a vertical screw jack for lifting and lowering the table K when the securing bolts are slackened to adjust the table.

Having now fully described my invention I declare that what I claim is:

1. In a machine for seaming lids on cans, in combination:—a horizontal driving shaft; a vertical shaft; a seaming head driven by said vertical shaft; spur gearing connecting the vertical shaft to the driving shaft; radially movable seaming rollers carried by the seaming head, a horizontally slidable cam-operated member, means connecting the said member to the seaming rollers by which the latter are moved radially by the said member, a cam for operating the slidable member; a vertically movable table in alignment with the seaming head, a horizontally slidable cam-operated member, connecting means between said member and the table by which when the member is moved horizontally the table is moved vertically, a cam for actuating the said member; lid stacking means; means for conveying the cans to a position in alignment with the stack of lids, then onto the moving table and thence to the discharge end of the machine, cams to operate the said conveying means; a lid locating and clenching mechanism adapted to transfer the lowermost lid of the stack of lids onto a can and to clamp it in position thereon, a lever adapted to operate the mechanism, a horizontally slidable cam-operated member, means connecting the said member to the said lever to operate it, a cam to operate the said member; a vertical cam shaft; a friction clutch comprising two elements with plain frictional surfaces pressed into abutting contact by adjustable springs, one of which elements is connected to the cam shaft; speed reducing gear connecting the other element to the driving shaft; the parts of the several connecting means primarily operated by the several above recited slidable cam-operated members being spaced in vertical succession in and with the said members moving in a common vertical plane passing through the axis of the cam shaft; the cams recited as operating the said members being mounted on the said cam shaft, each having a cam surface the generatrix of which is a line maintained parallel with the axis of the cam shaft.

2. In a machine for seaming lids on cans, in combination;—a horizontal driving shaft; a vertical shaft; a seaming head driven by said vertical shaft; spur gearing connecting the vertical shaft to the driving shaft; radially movable seaming rollers carried by the seaming head, a horizontally slideable cam-operated member, means connecting the said member to the seaming rollers by which the latter are moved radially when the 5 member is moved horizontally, a cam for operating the slideable member; a vertically movable table in alignment with the seaming head, transversely movable centering sectors carried by the table; a vertical rod having limited axial 10 movement relatively to the table; a spring attached to said rod resisting upward movement of the rod, a transverse pivot pin attached to the rod, pairs of links pivoted at their lower ends on the pivot pin, the upper ends extending outwards 15 and being pivoted to pins on the respective sectors, which links, when there is relative movement between the vertical rod and table as the latter is raised, pull the sectors inwardly and centre a can located between them; a horizontally 20 slideable cam-operated member, connecting means between said member and the table by which the latter is moved vertically when the member is moved horizontally, a cam for actuating the said member; lid stacking means; means for conveying 25 the cans to a position in alignment with the stack of lids, then onto the moving table and thence to the discharge end of the machine; cams to operate the said conveying means; a lid locating and clenching mechanism adapted to transfer the lowermost lid of the stack of lids onto the can and to 30 clench it in position thereon, a lever adapted to operate the mechanism, a horizontally slideable cam-operated member, means connecting the said member to the lever for operating the lid locating and clenching mechanism, a cam to operate the said member; a vertical cam shaft; a friction 35 clutch comprising two elements with plain frictional surfaces pressed into abutting contact by adjustable springs, one of which elements is connected to the cam shaft; speed reducing gear connecting the other element to the driving shaft; the parts of the several connecting means primarily 40 operated by the several above recited slideable cam-operated members being spaced in vertical succession in and with the said members moving in a common vertical plane passing through the axis of the cam shaft; the cams recited as operating the said members being mounted on the said cam shaft, and each having a cam surface the generatrix of which is a line maintained parallel to the axis of the cam shaft. 45
4. In a machine for seaming lids on cans, in combination;—a horizontal driving shaft; a vertical shaft; a seaming head driven by said vertical shaft; spur gearing connecting the vertical shaft to the driving shaft; radially movable seaming rollers carried by the seaming head, a horizontally 50 slideable cam-operated member, means connecting the said member to the seaming rollers by which the latter are moved radially when the said member is moved horizontally, a cam for operating the slideable member; a vertically movable table in 55 alignment with the seaming head; a horizontally slideable cam-operated member, connecting means between said member and the table which when the member is moved horizontally move the table vertically, a cam for actuating the said member; 60 lid stacking means; two pairs of adjacent parallel bars extending across the machine to which simultaneous reciprocating motion and oppositely directed to-and-fro angular movements are imparted, two parallel gripper bars respectively pivoted to levers keyed to the respective pairs of the parallel bars by which gripper bars the cans fed to the machine are in succession gripped and moved from under the stack of lids onto the moving table and thence to the delivery end of the machine; cam-operated means to reciprocate the parallel 65 bars longitudinally, a lay shaft parallel with the parallel bars; an operating lever keyed on said shaft; a lever on one of the bars of a pair of the adjacent parallel bars, a lever on one of 70 the parallel bars pivoted on an axis parallel with the parallel bars, a lever on one of the bars of the other adjacent pair of the parallel bars, radius links 75 connecting the operating lever to the respective levers on the bars, a horizontally slideable cam-operated member, means connecting the member to the operating lever which move the latter angularly when the member moves horizontally, a cam to operate the said member; a lid locating and clenching mechanism adapted to transfer the lowermost lid of the stack of lids onto the can and to 80 clench it in position thereon, a lever adapted to operate the mechanism, a horizontally slideable cam-operated member, means connecting the said member to the lever for operating the lid locating and clenching mechanism, a cam to operate the said member; a vertical cam shaft; a friction clutch comprising two elements with plain frictional surfaces pressed into abutting contact by adjustable springs, one of which elements is connected to the cam shaft; speed reducing gear connecting the other element to the driving shaft; the parts of the several connecting means primarily 85 operated by the several above recited slideable cam-operated members being spaced in vertical succession in and with the said members moving in a common vertical plane passing through the axis of the cam shaft; the cams recited as operating the said members being mounted on the said cam shaft, and each having a cam surface the generatrix of which is a line maintained parallel to the axis of the cam shaft. 90
3. In a machine for seaming lids on cans, in combination;—a horizontal driving shaft; a vertical shaft; a seaming head driven by said vertical shaft; spur gearing connecting the vertical shaft to the driving shaft; radially movable seaming rollers carried by the seaming head, a horizontally 95 slideable cam-operated member, means connecting the said member to the seaming rollers by which the latter are moved radially when the said member is moved horizontally, a cam for operating the slideable member; a vertically movable table in alignment with the seaming head, a horizontally slideable cam-operated member, connecting means between said member and the table which when the member is moved horizontally move the table vertically, a cam for actuating the said member; lid stacking means; two pairs of adjacent parallel bars extending across the machine to which simultaneous reciprocating motion and oppositely directed to-and-fro angular movements are imparted, two parallel gripper bars respectively pivoted to levers keyed to the respective pairs of the parallel bars by which gripper bars the cans fed to the machine are in succession gripped and moved from under the stack of lids onto the moving table and thence to the delivery end of the machine; cam-operated means to reciprocate the parallel bars longitudinally, a lay shaft parallel with the parallel bars; an operating lever keyed on said shaft; a lever on one of the bars of a pair of the adjacent parallel bars, a lever on one of 100 the parallel bars pivoted on an axis parallel with the parallel bars, a lever on one of the bars of the other adjacent pair of the parallel bars, radius links connecting the operating lever to the respective levers on the bars, a horizontally slideable cam-operated member, means connecting the member to the operating lever which move the latter angularly when the member moves horizontally, a cam to operate the said member; a lid locating and clenching mechanism adapted to transfer the lowermost lid of the stack of lids onto the can and to 105 clench it in position thereon, a lever adapted to operate the mechanism, a horizontally slideable cam-operated member, means connecting the said member to the lever for operating the lid locating and clenching mechanism, a cam to operate the said member; a vertical cam shaft; a friction clutch comprising two elements with plain frictional surfaces pressed into abutting contact by adjustable springs, one of which elements is connected to the cam shaft; speed reducing gear connecting the other element to the driving shaft; the parts of the several connecting means primarily 110 operated by the several above recited slideable cam-operated members being spaced in vertical succession in and with the said members moving in a common vertical plane passing through the axis of the cam shaft; the cams recited as operating the said members being mounted on the said cam shaft, and each having a cam surface the generatrix of which is a line maintained parallel to the axis of the cam shaft. 115

the bars of the other pair of the adjacent parallel bars, radius links connecting the operating lever to the respective levers on the bars, a horizontally slideable cam-operated member, a rack on the said member, a pinion on the lay shaft gearing with the rack, a cam to operate said member; a lid locating and clenching mechanism; a lever adapted to operate the mechanism, a lever loosely mounted on the lay shaft, a pawl pivoted on said lever, a part on the lay shaft adapted to engage the pawl whereupon the lay shaft operates the lid locating and clenching mechanism, a cam-operated part in the track of the cans and adapted to be displaced laterally by a can when the latter is under the stack of lids; a trip lever located in proximity to the pawl, which lever in its tripping position holds the pawl clear of the projection on the lay shaft, a lever located in proximity to the can-operated part and connected to the trip lever and moved by the cam-operated part, when the latter is displaced, so as to move the trip lever from its tripping position; a vertical cam shaft; a friction clutch comprising two elements with plain frictional surfaces pressed into abutting contact by adjustable springs, one of which elements is connected to the cam shaft; speed reducing gear connecting the other element to the driving shaft; the parts of the several connecting means primarily operated by the several above recited slideable cam-operated members being spaced in vertical succession in and with the said members moving in a common vertical plane passing through the axis of the cam shaft; the cams recited as operating the said members being mounted on the said cam shaft, and each having a cam surface the generatrix of which is a line maintained parallel to the axis of the cam shaft.

5. In a machine for seaming lids on cans, in combination;—a horizontal driving shaft; a vertical shaft; a seaming head driven by said vertical shaft; spur gearing connecting the vertical shaft to the driving shaft; radially movable seaming rollers carried by the seaming head; a grooved conical cam block concentrically mounted on the seaming head and axially movable thereon, means connecting the conical cam to the seaming rollers to move them into the seaming position, a bellcrank lever with a horizontal bowed arm fitted with pins engaging the groove in the conical cam, a horizontally slideable cam-operated member engaging a vertical arm of said lever, a cam to operate said member; a vertically movable table in alignment with the seaming head, a horizontally slideable cam-operated member, connecting means between said member and the table which when the member is moved horizontally move the table vertically, a cam for actuating the said member; lid stacking means; means for conveying the cans to a position in alignment with the stack of lids, then onto the moving table and thence to the discharge end of the machine; cams to operate the said conveying means; a lid locating and clenching mechanism adapted to transfer the lowermost lid of the stack of lids onto a can and to clench it in position thereon, a lever adapted to operate the mechanism, a horizontally slideable cam-operated member; means connecting the said member to the lever for operating the lid locating and clenching mechanism, whereby when the member is moved horizontally the clenching mechanism is operated, a cam to operate the said member; a vertical cam shaft; a friction clutch comprising two elements with plain frictional surfaces pressed into abutting contact by adjustable springs, one of which ele-

ments is connected to the cam shaft; speed reducing gear connecting the other element to the driving shaft; the parts of the several connecting means primarily operated by the several above recited slideable cam-operated members being spaced in vertical succession in and with the said members moving in a common vertical plane passing through the axis of the cam shaft; the cams recited as operating the said members being mounted on the said cam shaft, and each having a cam surface the generatrix of which is a line maintained parallel to the axis of the cam shaft. 5

6. In a machine for seaming lids on cans, in combination;—a horizontal driving shaft; a vertical shaft; a seaming head driven by said vertical shaft; spur gearing connecting the vertical shaft to the driving shaft; radially movable seaming rollers carried by the seaming head; cam-operated means for moving the seaming rollers into operative position; a casing enclosing the seaming head through the wall of which the horizontal shaft and a horizontally sliding part of the said means for actuating the seaming roller pass in fluid-tight manner, said casing having an aperture at the bottom in alignment with the seaming head, and the said aperture having a plain external surrounding facing, said casing also having a port opening into the wall of the aperture and into a second external facing on the casing; a rotary valve fitted to the second facing and adapted to connect the port in the casing in succession to three valve casing ports, gearing connecting the valve to the cam shaft; a vertically movable table, means carried by the table for centering the cans thereon, cam-operated means for reciprocating the table; an axially movable open-topped auxiliary sealing chamber arranged concentrically with the axis of the seaming head, its open top making joint in its upper position with the facing surrounding the aperture of the casing, said sealing chamber in its upper position enclosing the table and can thereon, and in its lower position having its open top slightly below the table top; means for reciprocating the auxiliary chamber, a cam for operating said means; a shutter valve adapted to close the aperture in the casing, means for opening and closing the shutter valve; a cam for operating said means; lid stacking means; a mechanism for locating the lowermost lid of the stack in place on a can and clenching it in position thereon, means for operating the said mechanism; a cam for operating said means; means for conveying the cans to a position in which they are in alignment with said stack, conveying them from the said position onto the movable table, and thence to the delivery side of the machine; cams for operating said conveying means; a vertical cam shaft on which all the above recited cams are located, said cam shafts being connected by a frictionally operated slipping clutch and speed reducing gear to the driving shaft. 10

7. In a machine for seaming lids on cans, the combination with, a horizontal driving shaft, a vertical cam shaft driven from the driving shaft, a seaming head driven from the driving shaft, means for operating the seaming rollers, a cam for operating said means, a vertically movable table in alignment with the seaming head, a cam for imparting reciprocating movement to the table, lid stacking means, a lid locating and clenching mechanism adapted to transfer the lowermost lid of the stack of lids onto the can and clench it in position thereon, and cam- 15

operated means for operating the clenching mechanism, of means for conveying the cans from a position in line with a stack of lids and thence to the delivery, comprising:—two pairs of adjacent parallel bars extending across the machine to which simultaneous reciprocating motion and oppositely directed to-and-fro angular movements are imparted; two parallel gripper bars respectively pivoted to levers keyed to the respective 5 pairs of adjacent parallel bars, by which gripper bars the cans fed to the machine are in succession gripped and moved from under the stack of lids onto the moving table and thence to the delivery end of the machine; cam-operated means 10 to reciprocate the parallel bars longitudinally; an operating lever pivoted on an axis parallel with the parallel bars; a lever on one of the bars of a pair of adjacent parallel bars; a lever on one of the bars of the other pair of adjacent 15 parallel bars; radius links connecting the operating lever to the respective levers on the bars; a horizontally slidable cam-operated member; means connecting the member to the operating lever which move the latter angularly when the 20 member moves horizontally.

8. In a machine for seaming lids on cans, the combination with, a horizontal driving shaft, a vertical cam shaft driven from the driving shaft, a seaming head driven from the driving shaft, a seaming 25 head driven from the driving shaft, a cam means for operating the seaming rollers, a cam for operating said means, a vertically movable table in alignment with the seaming head, a cam for imparting reciprocating movement to the table, lid stacking means, a lid locating and 30 clenching mechanism adapted to transfer the lowermost lid of the stack of lids onto the can and clench it in position thereon, cam-operated means for operating the clenching mechanism, means for conveying the cans from a position in line with the stack of lids and thence 35 to the delivery; means for operating the locating and clenching mechanism; and tripping means for rendering the said means inoperative except when a can is under the stack of lids; can transfer means, comprising:—two pairs 40 of adjacent parallel bars extending across the machine to which simultaneous reciprocating motion and oppositely directed to-and-fro angu-

lar movements are imparted, two parallel gripper bars respectively pivoted to levers keyed to the respective pairs of parallel bars by which gripper bars the cans fed to the machine are in succession gripped and moved from under the stack of lids onto the moving table and thence to the delivery end of the machine, cam-operated means to reciprocate the parallel bars longitudinally, a lay shaft parallel with the parallel bars; an operating lever keyed on said shaft; a lever 10 on one of the bars of a pair of adjacent parallel bars, a lever on one of the bars of the other pair of adjacent parallel bars, radius links connecting the operating lever to the respective levers on the bars, a horizontally slidable 15 cam-operated member, a rack on the said member, a pinion on the lay shaft gearing with the rack, a cam to operate said member; a lid locating and clenching mechanism, a lever adapted to operate the mechanism, a lever loosely mounted on the lay shaft and connected to the last mentioned lever, a pawl pivoted on said loosely mounted lever, a part on the lay shaft adapted to engage the pawl whereupon the lay shaft operates the lid locating and clenching mechanism, a cam-operated part in the track of the cans and adapted to be displaced laterally by a can when the latter is under the stack of lids, a trip lever located in proximity to the pawl, which lever in its tripping position holds the pawl 30 clear of the projection on the lay shaft, a lever located in proximity to the cam-operated part connected to the trip lever and moved by the cam-operated part, when the latter is displaced, so as to move the trip lever from its tripping 35 position.

9. The combination with the elements claimed in claim 7, of a chain conveyor on the can-receiving side of the machine and in line with the gripper bars; a rack-like extension of one 40 of the gripper bars; a spur wheel rotated by the said rack; a sprocket wheel for driving a chain; a free-wheel device connecting the spur wheel to the sprocket, whereby each time the gripper bars are moved rearwardly the conveyor chain is 45 moved forwardly.

FRANK OSCAR LEVI CHORLTON.
